DISPLAY HOLDER FOR DOLLS AND
SIMILAR ARTICLES

Barney Loerinc, New York, N. Y.

Application March 16, 1953, Serial No. 342,650

4 Claims. (Cl. 206—45.14)

1

This invention relates to retainers or holders for dolls and similar articles, and particularly adapted for the purpose of holding the doll or other article in a fixed and definitely-located position in a carton or other display or shipping container.

At the present time, certain types of dolls are packed within shallow types of display cartons, usually provided with a transparent front panel through which the doll and the costume worn by it can be plainly seen. Such dolls are usually clad in fancy costumes, including a flaring skirt which is spread or fanned outwardly in the carton to more effectively display it. In order to prevent wrinkling or disarray of the costume of the doll, as well as to prevent damage to the doll itself, it is desirable that the doll shall be fixedly held in a central position in the carton.

It is therefore one of the objects of the present invention to provide means by which a doll or other suitable article shall be securely mounted within a display or shipping carton and prevented from shifting movement therein so that the doll and its costume will reach the buyer or recipient in an undamaged and unwrinkled condition.

It is another object of the invention to provide a doll-retaining means which can be very inexpensively fabricated; which can be easily installed in the carton, and the doll readily mounted in it with a minimum of time required for the packing operation.

With these and other objects to be hereinafter set forth in view, I have devised the arrangements of parts to be hereafter described and more particularly pointed out in the claims appended thereto.

In the accompanying drawing wherein an illustrative embodiment of the invention is disclosed, Fig. 1 is a face view of the cardboard strip or sheet from which the retainer is formed;

Fig. 2 is a side elevation of the retainer as it appears when folded to its operative position;

Fig. 3 is a front elevation of the retainer folded into its operative position;

Fig. 4 is a top plan view of the retainer;

Fig. 5 is a plan view of a box or carton body, showing how the same is slotted to provide a band for holding the doll-retainer in place;

Fig. 6 is a plan view of a portion of the box body showing the retainer in position, but with the doll omitted to better disclose the construction of the retainer;

Fig. 7 is a sectional view taken substantially on the line 7—7 of Fig. 6, looking in the direction of the arrows;

2

Fig. 8 is a face view of the strip or sheet from which a second embodiment of the invention is produced;

Fig. 9 is a front elevation, with parts in section and other parts broken away, of the retainer of Fig. 8, showing the manner in which the same is held by the box or carton body.

Fig. 10 is a plan view of a box body intended for the reception of the retainer of Figs. 8 and 9, and Fig. 11 is a sectional view taken substantially on the line 11—11 of Fig. 9, looking in the direction of the arrows.

Referring to the drawings, and more particularly to Figs. 1 to 6 inclusive, 1 indicates the cardboard sheet or strip forming the doll-retaining device. The sheet or strip 1 has a portion 2 forming the body or back panel of the device, said portion including the shoulders 3 and 4. Above these shoulders in the sheet 1, is a transverse score or fold line 5 which is centrally interrupted by an inverted U-shaped slit 6 forming a tab portion 7. When the sheet or strip 1 is folded on the line 6 a forwardly-projecting flap 8 is produced, which flap is then provided with an aperture 9 produced by the inverted U-shaped slit 6.

Adjacent to its lower end, the body part 2 of the sheet or strip 1 is provided with a transverse fold or score line 10 on which the strip or sheet is folded. Located a short distance from the fold 10 or score line 10 is a second score line, indicated at 11. The strip of material located between the two score lines and indicated at 12, constitutes a foot support for a doll 13, the body of which extends through and is surrounded by the aperture

35 9, with the feet 14 of the doll resting against the strip 12 and also against a forwardly-extended tab 15 formed out of the body of the strip 1 by the production of the U-shaped slit 14a. At the lower end of the strip 1 is a locking tongue 16

40 which, when the device is in its folded and operative position, as shown in Figs. 2, 3, 4, 6 to 7 inclusive, extends upwardly at the front of the device and overlies the front of the body of the doll 13 and enters into the aperture 9 provided in the top flap 8.

It will be noted that the end portion of the locking tongue 16 is formed with the diverging edges 17 which form a dovetail extremity on the tongue 16 and which enters into locking engagement with the sides of the aperture 9, thus holding the tongue 16 securely in its erect position as shown in Figs. 2 and 7.

An example of a box intended for the reception of the doll-retainer is shown in Figs. 5 and 6, 55 wherein the box is shown as being in the form

of a shallow carton having a bottom wall 18 and the conventional upstanding four side walls 19. The box need not necessarily be of the square shape shown, but can be of any suitable shape according to the type and size of doll to be accommodated within it.

The bottom 18 of the box is formed with a pair of spaced, parallel slits 20 and 21, defining a retaining band 22 between them.

From the foregoing, the manner in which the device is installed in the box and is used to retain a doll or other article against shifting movement within the box, will be readily understood. While the retainer is in its flat condition, as shown in Fig. 1, it is thrust through the two slits 20 and 21 in the bottom of the box in such a manner that the band 22 located between the slits will overlie the front face of the body portion 2 of the strip 1. The shoulders 3 and 4 on the strip 1 will limit the extent to which the strip can be inserted through the slit 20. The strip is folded on the line 3 to bring its flap 8 forwardly, and the doll is then inserted down through the aperture 9. The strip is then folded on the line 10 to bring the strip 12 and its forwardly extending tab portion 15 to horizontal position, thus bringing these parts of the strip against the soles of the feet 14 of the doll. The toe portions of the feet of the doll will protrude through the opening 24 produced in the tongue 16 by the production of the slit 14a. The strip 1 is then folded on the line 11 and this will bring the locking tongue 16 to its upstanding position over the front of the body of the doll, and the upper end of the locking tongue is then inserted in the aperture 9 with which it will engage, thus holding the device in its erected position, and with the doll securely held by it.

In its erected position, the retainer affords protection for the body of the doll by means of the locking flap 16 which extends over and covers the lower portion of the body of the doll. The doll is held against upward shifting movement by the engagement of the front or toe portions of the feet of the doll in the aperture 24, and sidewise or angular shifting of the doll is prevented by the parts of the doll being surrounded by the apertures 9 and 24. Dolls of the character adapted to be held by the described device, are often provided with flowing garments of costumes which are flared out from the body of the doll and more or less fill the interior of the carton. In such case, the garments will completely cover and conceal the retainer, and while the doll will be securely held against shifting movement within the box, the means by which the doll is so held will be hidden and concealed by the garments worn by the doll.

In the embodiment of the invention disclosed in Figs. 8 to 11 inclusive, the sheet from which the retainer is produced is indicated at 31. The upper portion of this sheet is formed with a tongue 38 corresponding substantially to that shown at 8, which tongue is formed with an aperture 34 similar to that shown at 9. Extending downwardly from the transverse fold line 35 is a notch 49 serving as a locking element for attaching the sheet 31 to the bottom wall 48 of a box or carton within which the doll is to be contained.

Provided in the sheet 31 is a pair of spaced, upwardly extending parallel slits 41 and 42 defining a foot-supporting strip 32. At the upper ends of the slits 41 and 42 is a transverse fold or score line 45. A second transverse fold or score line

is shown at 46, with the U-shaped slit 47 providing the tab 44. The locking tongue is indicated at 49, the same being formed with the dovetailed end 50 for engagement with the aperture 34 in the manner described in connection with the locking tongue 16 and the aperture 9.

The box or carton shown in Fig. 10 is provided in its bottom wall 48 with a U-shaped slit 51 resulting in the production of a tab 52. In its operative position, as shown in Figs. 9 and 11, the sheet 31 constituting the doll retainer of this embodiment, is folded on the several score lines 35, 45 and 46. The doll is first placed in the position shown in Fig. 11 and substantially as described in connection with the first embodiment of the invention. When the sheet is folded on the lines 45 and 46, it will be noted that two legs 53 and 54 are formed. In fitting the retainer in the carton, the tab 52 of the carton is caused to engage with the notch 40, which engagement is a locking one due to the divergent edges 55 and 56 of the notch 40 frictionally engaging the edges of the tab 52. When the retainer 31 is thus engaged by the tab 52 it will be so located that the lower ends 51 and 53 of the legs 53 and 54 will be abutted against one of the side walls 59 of the carton. The retainer 31 will thus be confined between said side wall 59 and the tab 52 and prevented from shifting in any direction relatively to the carton. The doll is placed in position in the manner described with reference to Figs. 1 to 7, namely, by having the body of the doll surrounded by the aperture 34 and the feet rested against the support 32 and 44, with the feet of the doll protruding through the aperture 60 created by the formation of the tab 44.

The doll retainer is economically produced from a relatively small section of cardboard; it can be completely concealed by the costume of the doll; it will prevent shifting of the doll and avoid damage to the body of the doll as well as prevent disarrangement of the clothing on the doll. No gluing operations are required to attach the retainer to the carton, and many other advantages, apparent to those skilled in this art are attained in the device disclosed.

Having described an embodiment of the invention, it is obvious that the same is not to be restricted thereto, but is broad enough to cover all structures coming within the scope of the annexed claims.

What I claim is:

1. A retainer for dolls and similar articles comprising, a box having a bottom wall provided with spaced slits to form a band between them, a retainer in the form of a cardboard sheet having a body portion inserted through the slits and held behind the band, the body portion being provided at the top with a forwardly-extended apertured flap, the body portion being provided at its lower end with a forwardly-extended foot-rest for a doll, said foot-rest having its forward end provided with an upwardly-extended tongue, the tongue passing through the aperture in the upper flap, the tongue being provided with an opening adjacent its lower end and directly above the foot-rest for the reception of the feet of a doll disposed behind the tongue and having its feet disposed against the foot-rest.

2. A retainer for dolls and similar articles comprising a strip of cardboard provided with a back portion, a top flap extending forwardly therefrom and provided with an aperture extending around the body of a doll, the lower end 75 of the strip having a forwardly-extending foot-

5

support for the doll, a locking flap extending upwardly from the forward end of said foot support, said locking flap being engaged adjacent to its upper end with the aperture in the top flap, the locking flap being provided with an aperture through which the feet of the doll protrude, a carton and means on the wall of said carton engaging with parts of the strip to thereby attach said strip to the carton.

3. A retaining means for dolls comprising a carton formed with a tab in its bottom wall, a strip having a notch for engagement with the tab to thereby attach the strip to the bottom of the carton, the carton having a side wall, the strip having a portion confined between the tab and said side wall, said portion having an edge disposed against said side wall to thereby confine the strip between the tab and said side wall and preventing shifting of the strip relatively to the carton, the strip having a forwardly-bent lower end, said lower end being upturned to form a locking flap, said locking flap being apertured to permit the passage of the feet of a doll through said aperture, the strip being forwardly-bent at the top, said forwardly-bent portion being provided with an aperture extending around the body of a doll, and means on the locking flap for engagement with the aperture in the forwardly-bent portion at the top of the strip to thereby hold the locking flap in position to extend in front of and afford protection for that portion of the doll which is located between the forwardly-bent upper and lower portions of the strip.

6

4. A retaining means for dolls comprising a carton, a cardboard retaining strip having a part engaging the bottom of the carton to thereby attach the strip to the carton, the strip having a forwardly-extended flap at the top, said flap having an aperture surrounding the body of a doll, the strip having a forwardly-extending flap at its lower end constituting a foot support for the doll, the forward end of the foot support being upturned to form a locking flap, said locking flap constituting a protective panel extending in front of the portion of the doll located between the upper and lower forwardly-extending flaps, said locking flap having its upper end extending through the aperture in the top flap through which the body of the doll extends, said locking flap having an aperture at its lower end for permitting protrusion of the feet of the doll.
